HOBBY HORSE

Ben F. Prewitt, Montgomery, Ala.

Application May 7, 1954, Serial No. 428,261

8 Claims. (Cl. 155—56)

This invention relates to bouncing motion mechanism for use in amusement devices of the hobby horse type or for the more serious type of exercising device simulating the actions and motions of a horse solely as a result of muscular efforts of the rider.

It is a general object of the present invention to provide novel and improved bouncing motion mechanism of the type described.

More particularly it is an object of the invention to provide a motion mechanism for a seat for a rider which constrains the seat to move in a curved path highest at the center, through an intermediate portion only of which the seat remains horizontal.

An important object of the invention consists in the arrangement of a spring-resisted, pivoted rocker which acts intermediate a base to provide movable fulcrum for arms hinged thereto and to a seat and to provide limiting stops for the arms, between which their movement is unresisted.

Another important object of the invention comprises the arrangement of a device in which the rider is supported on a seat hinged at the upper ends of spaced parallel arms fulcrumed at their lower ends in such a manner as to provide restraint only at the ends of rocking movement of the arms.

A still further object of the invention resides in the construction and arrangement of a hobby and exercise horse adapted to oscillate forwardly and backwardly in an over-center movement under the muscular action of the rider and in which the path of rider movement and inclination of the horse changes gradually at each end of a stroke to vary the reaction between rider and horse for further muscular development.

Other and further objects of the invention will become more fully understood by those skilled in the art upon a consideration of the accompanying drawing and following specification, wherein is disclosed a single exemplary embodiment of the invention with the understanding that such changes and modifications may be made therein as fall within the scope of the appended claims without departing from the spirit of the invention.

In said drawing:

Fig. 1 is a side elevation of a bouncing motion mechanism for hobby and exercise horses; and

Fig. 2 is a transverse section taken on line 2—2 of Fig. 1.

The apparatus of the present invention is intended for amusement and/or exercising and may be constructed in sizes suitable for children of various ages or adults. It is adapted for use indoors or out in accordance with the character of materials used in construction. As illustrated the device is in the nature of means producing motions simulating a horseback ride, with the portion adapted to be used as a seat by the rider preferably of the stylized configuration of a horse, in order to provide for a safe seat and convenient hand holds, and foot rests, if desired. The simulation is in conformity with the mo-

2

tion developed by the mounting apparatus now to be described.

Referring to the drawings, it will be seen that the apparatus is mounted on a suitable rigid base platform 10 provided with a pair of upstanding bearing blocks 11 spaced laterally apart intermediate the ends of the platform and providing journals for trunnions or a transverse pin 12 about which rocker platform 15 is adapted to oscillate. This platform is of generally inverted triangular outline and of considerable width in the direction of the axis of pivot 12 for a purpose which will later appear and is resiliently biased against rocking about its pivot by means of the leaf spring 16, generally V-shaped, in order that the arms 17 thereof may bear against the flat under faces of the short sides of the triangular rocker. Between these arms the spring is bowed downwardly as shown to clear the center portion of the platform rocker and provide for mounting on the top surface of the base 10 between the blocks 11 where it is rigidly attached by bolts 18.

The simulated horse or any other suitable seating device 20 is shown mounted well above the rocker platform by means which will later be described. The seat may include a saddle simulation or merely a depression 21 in the back of the horse 20 which may be formed of any suitable material and shaped and colored to suit. For hand holds a transverse bar 22 may extend through the head portion, as shown, and if desired dangling or rigid stirrups 24 may be suspended from the horse, not only to facilitate mounting but to aid the rider in maintaining his balance when shifting his weight in the motion necessary to impart action to the device, since he is fully out of contact with the base 10.

The connection between the horse or seat and platform rocker comprises a pair of fore and aft spaced parallel arms 25, transversely pivoted as at 26 at longitudinally spaced positions on the horse near its bottom. Transverse pivot pins 28 are secured to the bars 25 at the level of the top surface 29 of the rocker platform, and these may rest on this surface and be held in position thereon to act as pivots by straps 30 suitably conformed to pass over the pins and be secured to the material of the platform. The parallel bars 25, however, have extensions 25' below their pivots 28 to be received into wells or pockets 31 in the rocker. The pockets are of triangular configuration in side elevation, substantially closed at the top where the bars enter them and have front and rear walls 32 and 33 substantially radial to the axes of the pivots 28 whereby to be engaged by the dependent extensions 25' of the bars 25 to define the two terminal positions of these bars relative to the platform.

This arrangement just described gives the horse a capability of movement so that any point thereon travels in a substantially arcuate path about a corresponding point on a line joining the centers of pivots 28 during movement resultant only from the pivoting of the arms 25. During this movement the horse remains substantially parallel to the base platform. Beginning from one end position of repose, as shown in solid lines in the figure, full stroke movement of the seat is completed by giving the horse sufficient impetus to carry over the vertical center from where it will fall, on the lowering side of the arc, until its motion is terminated by engagement of the dependent portions 25' against the rear walls 33 of the wells in the rocker, as shown in dotted lines. The substantial weight of the rider and the momentum imparted on the downward side of the arcuate path just described, results in bringing the lower ends of bars 25 into engagement with the pocket walls to instantly transfer to the rocker the energy of this movement, causing the rocker to pivot and flex its appropriate spring leaf which absorbs the shock. Any portion of the horse now travels in an

arc about the center of the pivot 12 and the horse no longer remains parallel to the base platform but achieves increasing tilt in the direction of its movement. The motion of the horse is slowly brought to a halt by the flexure of the appropriate leaf of the spring 16. This spring then recoils and returns the platform substantially to its intermediate position, at the same time imparting momentum to the horse and rider which can be augmented by his own muscular action to throw the horse over center and allow the action just described to be repeated in the reverse direction. The operator soon learns to exert body movement at the proper time and position in respect to the motion of the horse to maintain the continued oscillation of the same from maximum forward to maximum rear position, riding the same free between the stop positions of the lower ends of the arms in the wells but experiencing deceleration at each end of the stroke which is much less abrupt than it would be in the absence of the platform rocker and its buffer spring. The extent of the muscular action of the rider during this deceleration, as by rising in the stirrups, determines the amplitude of motion, as will be apparent.

If the bars 25 are rigid members the amplitude of motion will be somewhat restricted, but by making them of relatively flexible steel in the form of leaf springs much greater amplitude of motion can be achieved with less violent shock at the ends of the strokes, and a further change in the shape of the curved path travelled by the horse results because of the bending of these elements when the horse's movement is restricted by the spring 16 acting on the platform.

It will be appreciated that the arrangement of the fulcra, springs, pivots and the like are only illustrative and that many alternative forms may be made use of in accordance with the wishes of the constructor and yet achieve the same results.

I claim:

1. In a device of the type described, in combination, a base platform, a rocker platform unit, means pivoting the second platform to rock above and in respect to the first about a horizontal axis, spring means acting between said platforms to restrain relative movement, a seat unit, parallel arms respectively pivoted at fore and aft spaced locations on the under side of the seat unit, means pivoting the lower ends of said arms at similarly spaced locations on the said rocker platform unit, and means to limit the amount of angular movement between one of said units and said arms.

2. The device of claim 1 in which the movement limiting means are incorporated in the rocker platform unit.

3. The device of claim 1 in which the parallel arms supporting the seat are resilient flexible springs capable of considerable flexing under the weight and momentum of a rider in said seat.

4. An exercising device, in combination, a base, a seat unit, stirrups suspended from said seat unit, an intermediate element resiliently hinged to the base, parallel motion means connecting the unit to the intermediate element, and motion range limiting means for said parallel motion means.

5. The exercising means of claim 4 in which the parallel motion means includes spring blades bendable by momentum of the seat unit when the motion range limiting means become effective to thereby increase the range of movement of the seat unit.

6. In a bouncing motion device, in combination, a seat having transverse pivots spaced fore and aft below the seating surface thereof, a pair of parallel arms pivoted respectively on said pivots, a platform, pivots connecting the opposite ends of said arms to the upper surface of said platform, said arms being resilient flexible spring leaves unrestrained in respect to each set of pivots for movement thereon through a predetermined range and means cooperating between said arms near one end thereof and the part to which they are pivoted to abruptly limit the extent of free angular movement therebetween, said means comprising pockets in the platform and extensions on the arms below the lower pivots projecting into said pockets.

7. In a bouncing motion device, in combination, a seat having transverse pivots spaced fore and aft below the seating surface thereof, a pair of parallel arms pivoted respectively on said pivots, a platform, pivots connecting the opposite ends of said arms to the upper surface of said platform, said arms being resilient flexible spring leaves unrestrained in respect to each set of pivots for movement thereon through a predetermined range, means cooperating between said arms near one end thereof and the part to which they are pivoted to abruptly limit the extent of free angular movement therebetween, said means pivoting said platform to a base for rocking on an axis parallel to the pivots for said arms and below all of them and resilient resisting means positioned to limit the said rocking.

8. The combination of claim 7 in which the said platform is shaped as an inverted triangle and the resisting means comprises a V-shaped leaf spring having arms engaging the short sides of the triangle.
